UNITED STATES PATENT OFFICE

2,295,259

ELECTRIC SWITCH MECHANISM

Newton W. Coffey, El Paso, Tex.

Application September 2, 1939, Serial No. 293,299

4 Claims. (Cl. 200—5)

This invention relates to an electric switch mechanism and has relation more particularly to a mechanism of this kind especially designed and adapted for use with a lamp signal of the type comprised in my application for patent executed of even date herewith and which signal includes "Slow," "Right," "Left," "Stop," "Back" and taillight when the signal lamp is used at the rear of the car.

It is an object of the invention to provide a switch mechanism wherein the closing of the desired circuits is under control of the switch, gear shift and foot brake of the car, together with suitably operated members for closing the circuits for the "Right" and "Left" signals.

The invention also has for an object to provide a switch mechanism of this kind including mechanically operated blades for closing the circuits for the "Right" and "Left" signals and wherein such mechanically operated means is of a character to allow for the closing of either of the circuits at a predetermined point in advance of the turn and to be latched in such closed position until the car again travels straight ahead.

The invention consists in the details of construction and in the combination and arrangement of the several parts of my improved electric switch mechanism whereby certain important advantages are attained and the device rendered simpler, less expensive and otherwise more convenient and advantageous for use, as will be hereinafter more fully set forth.

The novel features of my invention will herein-after be definitely claimed.

In order that my invention may be the better understood, I will now proceed to describe the same with reference to the accompanying drawings, wherein—

Figure 1 is a view in top plan of a switch mechanism constructed in accordance with an embodiment of my invention;

Figure 2 is a sectional view taken substantially on the line 2—2 of Figure 1 and of Figure 4;

Figure 3 is a fragmentary view taken substantially on the same line as Figure 2 but showing certain of the parts in a second position;

Figure 4 is a top plan view of the mechanism as herein disclosed with the top plate or cover removed;

Figure 5 is a fragmentary sectional view taken substantially on the line 5—5 of Figure 2;

Figure 6 is a fragmentary detailed sectional view taken substantially on the line 6—6 of Figure 5;

Figure 7 is a diagrammatic view illustrating my

improved mechanism in electrical connection with a signal lamp;

Figure 8 is an elevational view of the preferred type of signal lamp.

5 As disclosed in the accompanying drawings, C denotes a casing of desired configuration and dimensions and which is to be placed as desired upon the body of a car. The bottom wall 1 of the casing has disposed therethrough an insulated plug 2 through which are directed the several conductors associated with the mechanism. The top of the casing C is closed by a cover or lid 3.

10 Within the casing C and resting upon the bottom wall thereof and arranged side by side are a series of spaced bridge members or supports 4, 5, 6, 7 and 8. These members are of suitable material non-conductive of electricity and the upper margin of each of these bridges or members has oppositely inclined portions a and b arranged on desired relative angularity.

15 The high portions of these bridges or members have secured to the opposite faces thereof and extending from above the posts 9 with which are 25 pivotally connected, as at 10, the intermediate portions of the elongated switch blades 11, 12, 13, 14, and 15 associated respectively with the bridges or members 4, 5, 6, 7 and 8. These blades 11, 12, 13, 14 and 15 have respectively the angularly related tail extensions 16, 17, 18, 19 and 20. The angle of each of these tail pieces with respect to its blade is such that by contact of said tail piece with the rear inclined portion a of an associated bridge or member the upward swinging movement of the blade proper is limited. The contact of the blade proper with the upper margin b of a bridge or supporting member will, of course, limit the extent of upward swinging movement of the associated tail piece.

20 The blade 11 when swung downwardly toward its bridge or supporting member 4 is received between the pairs of spring contacts 21, 22, 23 and its tail piece 16 when in its lowered position engages between pairs of spring contacts 24, 25.

25 The blade 12 when in its lowered or closed position is received between the pairs of spring contacts 26, 27 and 28 and its tail piece 17 is received between the pairs of spring contacts 29, 30. The blade 13 when in its lowered or closed position is received between the pairs of spring contacts 31, 32 and 33 while its tail piece 18

30 when in lowered or closed position is received between the pairs of spring contacts 34, 35. The blade 14 when in its lowered or closed position is received between the pairs of spring contacts

55

36, 37, 38 while its tail piece 19 when in lowered or closed position is received between the pairs of spring contacts 39, 40. The blade 15 when in its closed or lowered position is received between the pairs of spring contacts 41, 42, 43 while its tail piece 20 when lowered or in closed position is received between the pairs of spring contacts 44, 45.

The contacts 23 and 24 are electrically connected by a conductor c and the contact 24 is electrically connected with the contact 29 by a conductor d. The contact 30 is electrically connected with the contact 35 through a conductor e while the contact 34 is in electrical connection with the contact 39 through a conductor f. A contact 40 is in electrical connection with a contact 45 thru a conductor g. The contact 45 is in electrical connection through a conductor h with a suitable source E of electrical energy.

The contact 44 is in electrical connection with the contact 43 through a conductor i and the contact 43 is in electrical connection with the contact 38 through a conductor k. The contact 38 is in electrical connection with the contact 33 through a conductor m and the contact 33 is in electrical connection with the contact 28 thru a conductor n. The contact 26 is electrically connected with the contact 31 through the conductor o and the contact 31 is in electrical connection with the contact 36 through the conductor p. The contact 36 is in connection with the contact 41 through a conductor s.

A signal lamp L is preferably of a type as comprised in my application for patent Serial No. 293,300, filed on even date herewith and includes an illuminating element 46 for a taillight 47; an element 48 for a "Slow" signal 49; an element 50 for a "Right" signal 51; an element 52 for a "Left" signal 53; and element 54 for a "Stop" signal 55; and an element 55 for a "Back" signal 57.

The contact 21 has leading therefrom a conductor t comprised in the circuit for a tell tale signal 58 for the brake while the conductor o has leading therefrom a conductor v comprised in the circuit for the tell tale signal 59 for the entire system with which my switch mechanism may be employed.

Interposed between each of the several blades 11, 12, 13, 14 and 15 and its associated bridge or supporting member 4, 5, 6, 7 or 8 is an expansible coil spring 60 of a tension sufficient to throw the blade into its raised or open position and normally maintain the same in such position.

The wall 61 of the casing adjacent to the outer ends of the several switch blades and at a point therebelow is provided with an inwardly disposed shelf 62 upon which is positioned a bumper 63 to absorb undue shock when a switch blade is moved inwardly or downwardly into closed position.

The contact 22 is in electrical connection thru a conductor 64 with the element 48 for the "Slow" signal 49 and the contact 25 is in electrical connection thru a conductor 65 with the element 46 for the taillight 47. The contact 27 is in electrical connection through a conductor 66 with the element 56 for the "Back" signal 57. The contact 22 is in electrical connection through a conductor 67 with the element 50 associated with the "Right" signal 51 and the contact 42 is in electrical connection through a conductor 68 with the element 52 for the "Left" signal 53. The contact 37 is in electrical connection through the

conductor 69 with the element 54 for the "Stop" signal 55.

Carried by the cover or lid 3 and extending thereacross is a bracket plate 70. This bracket plate 70 above the blade 11 is provided with an opening 71 through which has vertical sliding movement a plunger 72. This plunger 72 is slidably disposed through a similarly positioned opening in the cover or lid 3 so that the lower end of the plunger 72 has contact from above with the blade 11.

This blade 11 has operative connection with the operating mechanism for the foot brake so that when the brake is applied the plunger 72 will be forced downwardly to bring the blade 11 into engagement with the contacts 21, 22, 23 and to have the tail piece 16 free of the contacts 24 and 25. The bracket 70 has a further opening 73 through which is slidably disposed a plunger 74 also working through the lid or cover member 3 for contact from above with the blade 12. This plunger 74 is adapted to be operated by the gear shift mechanism and as said mechanism is shifted or changed the plunger 74 is forced downwardly to move the blade 12 into engagement with the contacts 26, 27, 28 and to release the tail piece 17 from the contacts 29 and 30. The bracket 70 is also provided with adjacent openings 75 and 76 through which are slidably disposed respectively the plungers 77 and 78. The plungers 77 and 78 are positioned above the blade 13 and the plunger 77 is adapted to be forced downwardly upon operation of a suitable controlling member on the steering wheel of a car or otherwise placed to move the blade 13 into engagement with the contacts 31, 32, 33 when it is desired to make operation the "Right" signal 51. The plunger 78 is adapted to move downwardly when the steering wheel is operated to make a "Right" turn. As the plunger 78 moves downwardly a stop member 79 carried thereby contacts from above with a rock plate 80. This rock plate 80 at one end is provided with an opening 81 through which is freely disposed a pin 82 fixed to the lid or cover member 3 and bridging the space between said lid or cover member 3 and a marginal portion of the bracket plate 70. The opening 81 is of a size to readily allow the plate 80 to have up and down swinging movement. The end portion of the plate 80 having the opening 81 has bearing down thereon a coil spring 83 of desired tension encircling the pin 82 and interposed between said end portion of the plate 80 and the bracket plate 70. This plate 80 extends inwardly of the lid or cover member 3 a desired distance and its inner end is provided with a depending arm 84 extending through a slot 85 in the cover or lid 3 and positioned above a rock arm 86. This rock arm 86 is carried by a shaft 87 rotatably mounted within the upper portion of the casing C above the tail pieces 16, 17, 18, 19 and 20 adjacent their outer or free extremities and disposed in a direction transversely thereof.

This rock arm 86 constitutes an elongated side arm of a substantially U-shaped cradle, the intermediate or base portion 88 of which is positioned to the outer side of the shaft 87. A second short arm 89 of the cradle is operatively engaged with the shaft 87.

Extending along the base member 88 of the cradle and depending therefrom for a desired distance is a panel 90 of a material non-conductive of electricity. This panel 90 closely approaches the adjacent free extremities of the tail pieces 13, 14 and 15. Carried by this panel 90 and in

alignment with the tail piece 18 is a downwardly and inwardly inclined cam plate 91, the upper end of which providing a shoulder 92. As the blade 13 is forced downwardly by the plunger 17, the outer or free extremity of the tail piece 18 will contact with and ride by the cam plate 91 and engage from above with the shoulder 92 whereupon the blade 13 will be locked in its lowered or closed position with respect to the contacts 31, 32 and 33.

As the plunger 78 is caused to be moved downwardly or inwardly of the casing C as the steering wheel is turned to the right, the stop 79 will contact the rocker plate 80 and swing the same downwardly causing the arm 84 to contact the rock arm 86 and to press the same sufficiently to bring the panel 90 away from the tail piece 18 a distance sufficient to free the shoulder 92 from the tail piece 18. When the plunger 78 is in its lowered position it will maintain the blade 13 in its lowered or closed position until the steering wheels turn to bring the car to a straight ahead position whereupon the spring 60 associated with the blade 13 will throw the blade into its raised or open position.

In view of the foregoing it is believed to be apparent that the signal of a "Right" turn can be given at any distance in advance of the point of turning but upon completion of the turn the "Right" signal 51 will become ineffective.

The bracket plate 70 is also provided with the openings 93 and 94 through which are directed the plungers 95 and 96 which also pass through the lid or cover member 3 into the casing. These plungers 95 and 96 are above the blade 15 and the plunger 95 is adapted to move downwardly upon manipulation of a suitable operator upon the steering wheel or elsewhere within the body of the car when it is desired to indicate a "Left" turn. As this blade 15 moves into its lowered or closed position the free extremity of its tail piece 20 rides by a second cam plate 97 carried by the panel 90 to engage from above with the shoulder 95 provided at the top of the cam plate 97 whereby said blade 15 is held in its lowered or closed position.

The plunger 96 is adapted to be moved downwardly or inwardly of the casing C when the steering wheel is moved to the left and during which movement this plunger 96 soacts with the rocker plate 80 in the same manner and for the same purpose as hereinafter set forth with respect to the plunger 78.

Intermediate the cam plates 91 and 97 the panel 90 carries a cam plate 99 extending a considerable distance above the cam plates 91 and 97 as illustrated in Figures 2 and 5 of the drawings. This cam plate 99 is positioned in alignment with the rear or inner end of the tail piece 19 of the blade 14. The bracket plate 70 is provided with an opening 100 through which is slidably directed the plunger 101 also working through the lid or cover member 3 for contact from above with the blade 14. This plunger 101 is operatively engaged with the clutch mechanism so that as the clutch is released the plunger 101 will move downwardly or inwardly of the casing C and move the blade 14 into electrical connection with the contacts 36, 37 and 38 whereby the "Slow" signal 49 will become effective. It will be noted that if this clutch is released with either of the signals 51 or 53 in use, the contact of the tail piece 19 of the blade 14 with the cam plate 99 will rock the panel 90 outwardly to release either of the tail pieces 18 or 20 which may be

resting upon its respective shoulder 92 or 98. Upon such release the spring 60 coating with either of such blades 13 or 15 will throw such blade into its open or released position.

Without tracing the various circuits it is believed to be obvious from the foregoing description when considered in connection with the accompanying drawings, that various contact members are so connected with each other and the several switch blades have their tail pieces coacting therewith in a manner that the tell tale light 59 will burn at all times after the main switch 102 has been closed. It is also believed to be equally apparent that the various electrical connections are such as to maintain the lighting element 46 for the taillight 47 functioning except when either of the lighting elements 50 or 52 is burning. With my improved switch the lighting element 46 for the taillight 47 will burn at all times just so long as the switch 102 is closed except when the signal 51 or 53 is being used. The main switch 102 may be as desired but is preferably of a type to be under control of the usual ignition key.

25 The means for shifting the several plungers forms no part of the present invention and for which reason a detailed description and illustration of such means is believed to be unnecessary.

The panel 90 is constantly urged toward the tail pieces 16, 17, 18 and 19 by the retractile spring 103 suitably connected, as at 104, with a bracket 105 carried by the adjacent wall 1 of the casing C and to the intermediate member 88.

From the foregoing description it is thought to be obvious that an electric switch mechanism constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

1. An electric switch mechanism comprising a normally closed casing including top, bottom and side walls, a support mounted within the lower portion of the casing, said support being of a material non-conductive of electricity, the upper margin of the support having its end portions oppositely inclined, a switch blade pivotally supported by and above the support, a tail piece extending from the pivoted end portion of the blade and inclined with respect thereto, contacts carried by the opposite end portions of the support, contact of the tail piece with the adjacent inclined portion of the support limiting the movement of the blade away from one of the contacts with which the blade coacts, the tail piece when in engagement with the support being in connection with the contact member at the adjacent end portion of the support, an expansible member interposed between the support and the blade for normally maintaining the blade free of its contact or in open position, and a plunger above the blade and slidably disposed through the top wall of the casing, downward movement of the plunger forcing the blade into engagement with this contact and releasing the tail piece from its contact.

2. An electric switch mechanism comprising a

normally closed casing including top, bottom and side walls, a support mounted within the lower portion of the casing, said support being of a material non-conductive of electricity, the upper margin of the support having its end portions oppositely inclined, a switch blade pivotally supported by and above the support, a tail piece extending from the pivoted end portion of the blade and inclined with respect thereto, contacts carried by the opposite end portions of the support, contact of the tail piece with the adjacent inclined portion of the support limiting the movement of the blade away from one of the contacts with which the blade coacts, the tail piece when in engagement with the support being in connection with the contact member at the adjacent end portion of the support, an expansible member interposed between the support and the blade for normally maintaining the blade free of its contact or in open position, a plunger above the blade and slidably disposed through the top wall of the casing, downward movement of the plunger forcing the blade into engagement with this contact and releasing the tail piece from its contact, an inwardly disposed shelf carried by a side wall of the casing below the outer portion of the blade, and a bumper mounted on the shelf to absorb undue shock when the switch blade is moved by the plunger into engagement with its contact.

3. An electric switch mechanism comprising a normally closed casing including top, bottom and side walls, a support mounted within the lower portion of the casing, said support being of a material non-conductive of electricity, the upper margin of the support having its end portions oppositely inclined, a switch blade pivotally supported by and above the support, a tail piece extending from the pivoted end portion of the blade and inclined with respect thereto, contacts carried by the opposite end portions of the support, contact of the tail piece with the adjacent inclined portion of the support limiting the movement of the blade away from one of the contacts with which the blade coacts, the tail piece when in engagement with the support being in connection with the contact member at the adjacent end portion of the support, an expansible member interposed between the support and the blade for normally maintaining the blade free of its contact or in open position, a plunger above the blade and slidably disposed through the top wall of the casing, downward movement of the plunger forcing the blade into engagement with this contact and releasing the tail piece from its contact, a member within the casing outwardly of but in close proximity to the outer end of the tail piece, means for supporting said member for

swinging movement toward or from the tail piece, and a cam face plate carried by the face of the swinging member opposed to the outer end of the tail piece, said cam plate providing a shoulder, the outer end of the tail piece contacting with and riding on said cam face when the switch blade is swung toward its contact, said swinging member, when the switch blade is in engagement with its contact, swinging in a direction to bring the shoulder of the cam plate below the tail piece to hold the switch blade against movement away from its contact.

4. An electric switch mechanism comprising a normally closed casing including top, bottom and side walls, a support mounted within the lower portion of the casing, said support being of a material non-conductive of electricity, the upper margin of the support having its end portions oppositely inclined, a switch blade pivotally supported by and above the support, a tail piece extending from the pivoted end portion of the blade and inclined with respect thereto, contacts carried by the opposite end portions of the support, contact of the tail piece with the adjacent inclined portion of the support limiting the movement of the blade away from one of the contacts with which the blade coacts, the tail piece when in engagement with the support being in connection with the contact member at the adjacent end portion of the support, an expansible member interposed between the support and the blade for normally maintaining the blade free of its contact or in open position, a plunger above the blade and slidably disposed through the top wall of the casing, downward movement of the plunger forcing the blade into engagement with this contact and releasing the tail piece from its contact, a member within the casing outwardly of but in close proximity to the outer end of the tail piece, means for supporting said member for swinging movement toward or from the tail piece, a cam face plate carried by the face of the swinging member opposed to the outer end of the tail piece, said cam plate providing a shoulder, the outer end of the tail piece contacting with and riding on said cam face when the switch blade is swung toward its contact, said swinging member, when the switch blade is in engagement with its contact, swinging in a direction to bring the shoulder of the cam plate below the tail piece to hold the switch blade against movement away from its contact, and means operating independently of the plunger for moving said swinging member to release the shoulder of the cam plate from the tail piece to permit the blade to return to its open position.

NEWTON W. COFFEY.
